ROTARY MOWER BASE

Thomas M. Topp, Parkville, Mo., assignor to Food Machinery and Chemical Corporation, San Jose, Calif., a corporation of Delaware

Application January 18, 1955, Serial No. 34,051

Term of patent 14 years

(Cl. D40—1)

FIG. 1

FIG. 2

FIG. 3

FIG. 4

Fig. 1 is a plan view of a rotary mower base, showing my new design.

Fig. 2 is a side elevation of the base of Fig. 1.

Fig. 3 is a front elevation of the base.

Fig. 4 is a rear elevation of the base.

The opposite side of the rotary mower base is substantially the same in appearance as the side shown.

I claim:

The ornamental design for a rotary mower base, as shown and described.
